UNITED STATES PATENT OFFICE.

DONHAM OWEN, OF BERKELEY, CALIFORNIA.

ADJUSTABLE DESK.

Application filed November 9, 1920. Serial No. 422,829.

To all whom it may concern:

Be it known that I, DONHAM OWEN, a citizen of the United States, residing at Berkeley, in the county of Alameda and State of California, have invented certain new and useful Improvements in Adjustable Desks, of which the following is a specification.

My invention is an improved adjustable desk.

My invention is illustrated in the accompanying drawing which forms a part of this specification.

Referring to the drawing:

Figure 1 is a side elevation of my desk partly broken away to illustrate certain parts.

Figure 2 is a front elevation of my desk.

Figure 3 is a rear elevation of my desk partly broken away to show certain parts.

Figure 4 is an enlarged side view of the upper part of the desk partly in section showing the means for adjusting the inclination of the desk top.

Figure 5 is a vertical section of the desk taken on line 5—5 of Figure 3.

Figure 6 is a section taken on line 6—6 of Figure 3.

Figure 7 is an enlarged fragmentary view 30 of the ratchets.

In the drawing 1 indicates a standard having a base 2, and a seat supporting member 3. The standard 1 is formed with a vertical slot 4 extending downwardly from the top of the standard and with a slot 5 extending horizontally into the lower portion of slot 4. In the slot 4 a post 6 is reciprocatively mounted to the top of which is pivoted a desk top 7 by means of a pivot 8 extending through the top of said post and through lugs 9 depending from said top at each side of the post. One member of a V-shaped rod 10 is reciprocatively mounted horizontally in the top of post 6 while the other member of said bar engages the under side of the desk top 7 to hold the top at the desired inclination. By moving said rod 10 forwardly and backwardly the inclination of the top 7 may be varied. A pawl 11 extending through the slots 5 and 4 is pivoted at 12 in the rear part of the standard 1 and is provided with a slot 13 through which extends a pin 14 secured in the lower end of post 6. A ratchet 15 is secured to the rear 55 of standard 1 at one side of the slot 5 which

is engaged by pawl 11 to hold the desk top 7 at the desired elevation, said top being raised and lowered by the pawl.

The seat supporting member 3 is formed with a vertical slot 16 extending through the top thereof in which is reciprocatively mounted a seat post 17 on the top of which post a seat 18 is pivotally mounted by a standard seat pivot 19 in the usual manner. The seat supporting member 3 is also formed with a slot 20 extending from the slot 16 through the side of the member.

A pawl 21 extending through slots 20 and 16 is pivoted in the rear portion of the seat supporting member at 22 and is provided with a slot 23 through which extends a pin 24 on the lower end of post 17. A ratchet 25 is secured to the seat supporting member 3 at one side of slot 20 which is engaged by pawl 21 to support the seat 18 at the desired elevation; the seat being raised and lowered by said lever. A vertical bearing 26 is formed in the rear portion of standard 1 in which a rod 27 is reciprocatively mounted. The lower end of rod 27 is bent rearwardly and extends through a slot 28 in the standard 1 and is connected to seat post 17, said post supporting the rod, while the upper end of said rod is bent rearwardly and extends through a vertical slot 29 in the upper rear part of standard 1 and is connected to a seat back 30, supporting said seat back.

Bolts 31 secured to the back extend into vertical slots 32 in the upper rear part of standard 1, said slots being widened at 35 their inner sides to receive heads 33 on said bolts, thus holding the back straight upon the standard and preventing the back from inclining sidewise.

The teeth of the ratchets 15 and 25 are formed with notches 35 in which respectively rest the pawls 11 and 21 whereby the pawls are prevented from disengaging the ratchets until lifted out of said notches.

Having described my invention, I claim:

A desk including a standard, a vertical post mounted in said standard, a desk top pivotally mounted on said post, a V-shaped rod, one member of which is reciprocatively mounted in said post, while its other member engages the under side of said top for adjusting the inclination of said top.

In testimony whereof I affix my signature.

DONHAM OWEN.
